G. R. DOBBINS

ELECTRIC SWITCH

Filed May 8, 1922

UNITED STATES PATENT OFFICE.

GEORGE R. DOBBINS, OF ALHAMBRA, CALIFORNIA, ASSIGNOR OF ONE-FOURTH TO H. H. HAMMOND AND ONE-FOURTH TO WILLIAM R. H. MILLER, BOTH OF LOS ANGELES, CALIFORNIA.

ELECTRIC SWITCH.

Application filed May 8, 1922. Serial No. 559,406.

To all whom it may concern:

Be it known that I, GEORGE R. DOBBINS, a citizen of the United States, residing at Alhambra, in the county of Los Angeles and 5 State of California, have invented a new and useful Electric Switch, of which the following is a specification.

This invention relates to an electric switch of a type that, when open, is latched so that 10 the switch cannot be accidentally closed.

An object of the invention is to produce a switch of this type that is suitable for use in connection with a burglar or hold-up alarm. It is desirable to place the switch, 15 for closing an alarm circuit, in a position that is convenient for operation and where it can be operated without the knowledge of thieves who may be positioned close to the operator. This switch is especially useful 20 mounted in the floor of a bank or other place of business so that it can be operated by the foot of a bank teller or any other person authorized to set off the alarm. It will be readily understood that a switch of this 25 character, mounted in the floor, should be of such construction that accidental striking of it with the foot will not cause it to close the circuit which it controls.

The accompanying drawings illustrate the 30 invention:

Figure 1 is a plan view of a switch constructed in accordance with the provisions of this invention, the switch arm being shown in circuit-breaking position in solid 35 lines and being indicated in circuit closing position in broken lines.

Fig. 2 is a sectional elevation on the irregular line indicated by 2-2, Fig. 1, the push button and contact arm being indicated in 40 circuit-closing position in dotted lines.

Fig. 3 is a sectional elevation on the irregular line indicated by 3-3, Fig. 2, the contact arm being indicated in circuit-closing position in dotted lines.

Fig. 4 is a fragmental sectional elevation on the line indicated by 4-4, Fig. 2, the push button being shown depressed in dotted lines.

There is provided a floor plate 5 adapted 50 to be secured by screws 6 to the floor or other surface in which the switch is mounted. Such floor or surface is indicated at 7. Secured by posts 8 to the plate 5 is a base plate 9 provided with stationary electric con-

tacts 10 which are insulated from the plate 55 9 as indicated at 11. The contacts 10 are formed by the inner ends of binding posts 12 to which the wires of the electric circuit that is to be controlled are connected, as will be readily understood, so that the switch will 60 be in the circuit. The contacts 10 are adapted to be engaged by a movable spring electric contact 13 adapted to bridge across the space between the contacts 10. The intermediate portion of the contact 13 is 65 secured by a screw 14, insulated at 15, to one end of an arm 16 which is pivoted near its other end at 17 to a pair of brackets 18 secured to the under face of the plate 5, 70 as clearly shown in Figure 4.

The arm 16 is provided adjacent the pivot 17 with a downward projection 42 having a pair of oppositely disposed beveled faces 19, 20, lying at an angle to each other. The face 19, when the arm 16 is in the "off" position, as 75 shown in Figure 2, engages a spring 21 secured at one end to the plate 9. When the arm 17 is in the "on" position the bevel face 20 engages the spring 21. To effect this the spring 21 is provided with portions 22, 23 lying at an angle to each other and alternately engaged by the faces 19, 20 according to whether the arm 16 is in circuit-opening or circuit-closing positions. Thus the spring 21 will hold the arm 16 in either the 80 "off" or "on" position and said spring also functions to snap the arm 16 to and from the contact closing position so as to avoid arcing between the contacts 10 and 13.

The plate 5 is provided with a recess 24, 90 and pivoted at 25 to shift within this recess is an operating member 26 in the form of a disc provided with a projecting ear 27. The pivot 25 passes through the ear 27. The member 26 is provided with an up- 95 standing boss 28 in which is slidably mounted the stem 29 of a push button 30. The stem 29 projects through a hole 31 in the plate 5 and is provided with an annular groove 32, which is sufficiently wide to receive the marginal portion of the hole 31. The member 26 is provided with a slot 33 100 communicating with the hole 31 and constructed in an arc whose center is the axis of the pivot 25. The slot 33 is of less width than the diameter of the hole 31 and is slightly wider than the diameter of the reduced portion of the stem 29 so that, when 105

the push button 30 is depressed to aline the groove 32 with the slot 33, said push button may be moved out of the hole 31 into the slot 33. When the push button is in the slot 33, the under face of the plate 5 engages the shoulder 34 formed by the lower wall of the groove 32, thus holding the push button depressed.

When the push button is in its upper position the groove 32 lies above the level of the slot 33. The push button 30, when in the hole 31, is yieldingly held against depression by a plunger 35 slidably mounted in the upper end of a spring chamber 36 containing a coil spring 37 which engages the inner end of the plunger 35 to yieldingly hold said plunger in contact with the push button 30. The spring chamber 36 is provided with an internal shoulder 38 which engages in a longitudinal groove 39 in the plunger 35, said shoulder 38 limiting outward movement of the plunger.

When the push button 30 is depressed and moved from the hole 31 along the slot 33 it strikes a projection 40 on the upper face of the arm 16, if said arm is in the circuit-breaking position shown in solid lines in Figure 2, so as to swing said arm downwardly to the position indicated by dotted lines to cause the face 19 to leave the spring face 22 and to cause the face 20 to engage the spring face 23; whereupon said spring will further actuate the arm 16 to move the contact 13 into engagement with the contacts 10 and hold it in that position. This of course closes the circuit in which the switch has been connected.

When it is desired to open the circuit and reset the switch, the push button 30 will be retracted along the slot 33 into the hole 31. In this movement the lower end of the push button strikes a projection 41 on the upper face of the arm 16, said projection being on the opposite side of the pivot 17 from the projection 40. Engagement of the push button with the projection 41 swings the arm 16 upwardly to disengage the contact 13 from the contacts 10, thus opening the circuit. When the push button is thus returned to position in the hole 31 it engages and depresses the plunger 35 and, when released, is pushed upwardly by said plunger so as to bring the groove 32 out of registration with the slot 33.

From the foregoing it will be clear that, when the push button 30 is in its upper position in the hole 31, accidental striking of said button with the foot of a person walking on the floor, or otherwise, cannot move the push button into position to close the switch. If a person tread on the push button 30, it will of course be depressed, but cannot effect closing of the circuit since it is also necessary to move the push button laterally.

In practice, the switch will preferably be installed in the floor in position to be readily operated by the foot of a teller or other person authorized to set off an alarm connected in circuit with the switch. As soon as the presence of thieyes is noted by the teller or other person adjacent the switch, he will tread on the push button 30 to depress it, and he will then move his foot laterally, to the right in Figure 1, to operate the switch in the manner hereinbefore described so as to energize the alarm. The switch may be advantageously employed in connection with the hold-up alarm disclosed in my copending application Serial No. 559,407, filed May 8th, 1922, but may, of course, be used with any other suitable alarm.

I claim:

1. In an electric switch, the combination of a push button mounted for endwise and lateral movements, means yieldingly holding the push button in one position, means locking the push button against lateral movement when in said position, and means operable by lateral motion of the push button to close an electric circuit.

2. In an electric switch, a movably mounted operating member, a push button mounted to move endwise in the operating member and to move laterally with said member, means to hold the push button depressed when the operating member is moved, and means operable by the push button upon movement of the operating member to close an electric circuit.

3. In an electric switch, a movably mounted operating member, a push button mounted to move endwise in the operating member and to move laterally with said member, means yieldingly holding the push button in one position, means locking the push button against lateral movement when in said position, means to hold the push button depressed when the operating member is moved, and means operable by the push button upon movement of the operating member to close an electric circuit.

4. In an electric switch, the combination of a push button mounted for endwise and lateral movements, means yieldingly holding the push button in raised position, means locking the push button against lateral movement when in said position, means to hold the push button depressed when it is moved endwise and laterally, and means operable by lateral motion of the push button to close an electric contact.

5. In an electric switch, the combination of a pivoted arm, an electric contact carried by said arm, projections on the arm on opposite sides of the pivot, a second electric contact in position to be engaged by the first contact when the arm is in one position, means to yieldingly hold the arm with its

- contact engaged with or disengaged from the second contact, a member **mounted to** shift laterally from a position where it is disengaged from the arm into engagement 5 with one or the other of the projections according to whether the arm is in contact-engaging or contact-disengaging position, and means to hold said member against such lateral shifting when said member is in the 10 disengaged position.
6. In an electric switch, the combination of a pivoted arm, an electric contact carried by said arm, projections on the arm on opposite sides of the pivot, a second electric 15 contact in position to be engaged by the first contact when the arm is in one position, a third projection on the arm provided with beveled faces positioned at an angle to each other, a spring having faces positioned at 20 an angle to each other, one of the spring faces engaging one of the arm faces when the arm is in contact-closing position, and the other spring face engaging the other arm face when the arm is in contact-disengaging position, a member mounted to shift 25 laterally from a position where it is dis-
- engaged from the arm into engagement with one or the other of the first named projections according to whether the arm is in one or the other of its positions, and means 30 to hold said member against such lateral shifting when said member is in the disengaged position.
7. In an electric switch, the combination of an electric contact, means movable into different positions provided with an electric contact engageable with the first contact when said means are in one position, means movable into different planes and operable in one plane to one position to operate the 35 first means to close the contacts and operable in the same plane to another position to operate the first means to open the contacts, and means to prevent movement of the second means in the other plane. 40
- 45

Signed at Los Angeles, Cal., this 1st day of May 1922.
